UNITED STATES PATENT OFFICE.

CHARLES PFANSCHMIDT, OF CHICAGO, ILLINOIS, ASSIGNOR TO THEO. A. KOCHS COMPANY, OF CHICAGO, ILLINOIS, A CORPORATION OF ILLINOIS.

COMBINED HEAD-REST AND SERVER FOR BARBERS' CHAIRS.

968,403.

Specification of Letters Patent. Patented Aug. 23, 1910.

Application filed September 29, 1908. Serial No. 455,383.

To all whom it may concern:

Be it known that I, CHARLES PFANSCHMIDT, a citizen of the United States, residing at Chicago, in the county of Cook and State of Illinois, have invented certain new and useful Improvements in Combined Head-Rests and Servers for Barbers' Chairs, of which the following is a specification.

This invention relates to the construction and mounting for the head rest of a barber's chair, which can be used either with or without the server hereinafter described.

The object of the invention is to so construct the head rest that it can be thrown down to a position in which it will not interfere with hair cutting and similar operations and without being actually removed from the chair, as is the usual practice.

Another object of the invention is to so construct the head rest that it will be sanitary and hygienic and at the same time light and comfortable.

A further object is to provide a mounting for the serving roll and cutter so that additional attaching means for these members will not be required; and further objects will appear from a detailed description of the invention, which consists in the features of construction and combination of parts hereinafter described and claimed.

In the drawings, Figure 1 is an elevation of the head rest, showing the roll and cutter; Fig. 2 a sectional elevation of the same in forward or operative position; Fig. 3 a similar view showing the head rest thrown back into non-operative position; Fig. 4 a sectional detail showing the locking rod for the rest; Fig. 5 a cross sectional view of the paper cutter; Fig. 6 a longitudinal sectional view of the same; Fig. 7 a side elevation of the paper roll spindle; Fig. 8 a longitudinal sectional view of the same; Fig. 9 a top elevation of the head rest showing the pad; and Fig. 10 a similar view showing the pad removed.

The head rest, as a whole, is secured to an adjusting bar or shank 11 provided, on its rear face, with the usual ratchet teeth 12, which bar or shank is fitted to slide within a guideway 13 in the back of the chair. The upper end of the bar or shank is provided with side ears 14 and an intermediate disk 15, which latter, on its forward side, is provided with a tooth 16 forming a stop or abutment for limiting the forward move-

ment of the head. The disk is further provided, near its periphery and immediately above the tooth 16, with a plurality of holes 17, and is further provided, in its center, with a hole 18, through which is entered a pivot pin 19, which also passes through the side ears 14.

The head proper comprises a pair of open side frames 20 of generally triangular shape, which are connected by means of a cross bar 21 to which is welded or otherwise secured a bracket plate 22 provided with a pair of tongues 23 which are suitably spaced and positioned to straddle the disk 15 and enter the spaces intermediate said disk and the ears 14, the tongues having the pivot pin 19 entered through them, which pin serves to pivot the head to the shank. The outer, or free edges 24 of the side frames are slightly curved in contour and are connected, at suitable intervals, by coil springs 25 which provide a resilient or yielding surface for the support of a cushion pad 26 which affords a smooth soft surface for the head of the occupant of the chair. The cushion is held in place on the springs by providing folds or laps 27 in the covering of the cushion which surround the two outer springs, the cushion being thus held tightly over and in close contact with the intermediate springs. 85

One of the side frames is provided, at its lower corner, with a depending lug 28 which has outwardly projecting therefrom a boss 29 which is beveled on its outer face 30 and is intended to coöperate with a cam 31 similarly beveled which is formed on the inner surface of a milled thumb wheel 32. The cam 31 has inwardly projecting therefrom a locking rod 33, which is slidably and rotatably entered through the boss 29 and the lug 28 and projects through a hole 34 in the adjacent tongue 23, and, when the cam or the beveled surfaces are in register, the rod is of a proper length to enter one of the holes 17 in the disk 15. A coil spring 35 which encircles the locking rod, near its outer end, serves to hold the rod normally in its inwardly projected position, permitting, however, a retraction of the rod, when the thumb wheel is turned to force the cam surfaces out of register with one another. Intermediate the side frames, near the front of the head rest, is a rod or spindle 36. The spindle is provided, on one end, with an outwardly projecting fixed pin 37, which is ro- 110

tatably mounted in the adjacent frame of the head rest and coöperates with a movable pin 38 which terminates, at its outer end, in a thumb nut 39 and is provided with screw threads 40 adjacent the thumb nut, which permit the removable pin to be entered into the companion frame of the head in alignment with the fixed pin 37. The inner or smooth end of the movable pin is passed through a bushing 41 and abuts against a small disk 42 which is backed by a spring 43 located within a bore 44 in the end of the spindle, the construction being such that the spring will be compressed and the opposite end of the spindle forced against the inner face of the adjacent portion of the frame, thereby securing sufficient friction to prevent free movement of the spindle, save only when subjected to a pull exerted on the paper carried thereby.

In order to prevent rotation of the roll of paper around the spindle, the latter is provided, in one side, with a longitudinally extending slot 45 which receives a normally bowed spring 46 which is fixedly secured to the spindle at its inturned end 47, the opposite end being free to slide within the groove as the spring is compressed into the position shown in Fig. 8. The spindle is adapted to receive a roll of serving paper 48, which is adapted to be fed up and over the head cushion and through a cutter 49 which is in the form of a plate 50 provided with a serrated cutting edge 51, which plate is provided, at its end, with ears 52. The cutter plate coöperates with a cutter frame 53 of channel formation, through a slot 54, in the upper surface of which the serving paper is fed. The lower wall of the channel frame is provided, at regular intervals, with outwardly projecting lugs 55 which register with slots 56 in the cutter plate, over which lugs the serving paper is carried prior to its being brought into register with the edge of the knife. A rod 57 is entered through the side frames of the head, through the ears 52 on the cutter plate, and through the inturned ends 58 of the channel shaped cutter frame, which rod serves to pivot the cutter plate to the cutter frame and secure the entire cutter mechanism between the side frames of the head rest. A spring 59 is provided, which serves to normally hold the slots 56 in the cutter plate in register with the lugs 55 on the lower edge of the cutter frame. In order to secure the necessary rigidity of the cutter frame, a lug 60 is provided on each of the end frames, against which lugs the rear face of the channeled cutter frame abuts and to which it is secured by means of rivets 61 or other attaching means.

In use, when it is desired to throw the head rest to its foremost position, as shown in Fig. 2, the thumb wheel is turned to re-

tract the locking rod by the action of cams, after which the head rest may be thrown forward until the bracket plate is brought into abutment with the tooth 16, which positions the head rest under ordinary conditions of use. In this position the locking rod can be released to engage the foremost hole 17 which holds the head rest in such adjusted position and prevents its displacement by movements of the head of the occupant of the chair. If other adjustments are desired, they can be secured by bringing the locking rod into register with a selected one of the holes provided to receive it. In using the serving paper, the end thereof is drawn forward from the roll and carried over the head cushion and entered through the cutting mechanism between the cutter plate and the lugs on the cutter frame, so that when the cutter plate is released the spring will hold the plate in close engagement with the face of the frame, thereby holding the lugs in register with the slots and clamping the paper against displacement, due to movements of the head of the occupant of the chair. When it is desirable to tear off the used portion of the paper, the barber inserts the tips of his fingers under the projecting edge of the cutter plate and in contact with the end of the paper, which projects slightly beyond the line of the lugs which clamp it, and a slight lifting movement of the barber's hand will raise the cutter plate, thereby unclamping the paper and at the same time pull forward the paper sufficiently to cause it to project beyond the serrated edge of the plate, after which the paper can be unrolled to the extent desired and torn off by engagement of the upper with the serrated edge of the cutter plate.

The spring supported pad affords an extremely comfortable rest for the head and at the same time practically no padding which might afford lodgment for dirt and vermin is provided in the head rest, which renders it clean and sanitary. The method of mounting the head rest is one which permits quick adjustment and obviates the necessity for a complete removal of the head rest from the barber's chair.

What I regard as new and desire to secure by Letters Patent is:

In combination with a head rest for barbers' chairs, an adjusting bar, angular adjusting means for the head rest, comprising outer and intermediate ears on the adjusting bar, companion ears carried by the head rest, entered between the outer and intermediate ears of the adjusting bar, means for connecting the ears, said means serving as a pivotal mounting to permit the head rest to be swung around the adjusting bar during the angular adjustment thereof, the intermediate ear of the adjusting bar having a single hole therein, and one of the ears

on the head rest having a plurality of holes therein adapted to register with the hole in the ear of the adjusting bar as the head rest is swung around, a lug having a cam surface secured to the head rest, a locking pin passing through said lug and capable of rotation therein, a collar having a cam surface secured to the locking pin, the pin, when projected, passing through a selected hole 5 in the ear of the head rest and a hole in the ear of the adjusting bar, and serving to lock the head rest against rotative movement and maintain it in desired position of angular adjustment, the rotation of the pin causing 10 the two cam surfaces to co-act and withdraw 15

the pin from the selected hole in the ear of the head rest and permit the angular adjustment of the head rest, the movement of the locking pin being insufficient to withdraw it from the ear of the adjusting bar, whereby 20 said ear serves as a mounting and guide for the acting end of the pin, and a spring adapted to project the pin into locking position when a counter-rotative movement is imparted thereto, substantially as described. 25
